UNITED STATES PATENT OFFICE.

CHARLES A. HULTQUIST, OF LOS ANGELES, CALIFORNIA.

DRILLING-MACHINE.

1,283,477.

Specification of Letters Patent. Patented July 17, 1917.

Application filed January 22, 1917. Serial No. 143,648.

To all whom it may concern:

Be it known that I, CHARLES A. HULTQUIST, a citizen of the United States, residing at Los Angeles, in the county of Los Angeles and State of California, have invented a new and useful Drilling-Machine, of which the following is a specification.

This invention relates to machines of the character designed for drilling and more especially in some respects to that type of drilling machine in which a stream of water is employed to minimize the production of dust and to flush the borings from the hole being drilled.

15 An object of this invention is to prevent the pinching or cutting off of the air and water pipe.

Another object is to make provision for the utilization of exhaust air from the cylinder for normally accelerating the flow of water, carrying away the borings, and for the utilization at times of live air for acceleration of the flow of the water for cleaning out the duct and grooves of the drill 25 steel when said grooves become plugged up with clay or other tenacious material.

Another object is to effect the foregoing by a comparatively simple construction and one that is reliable in operation.

30 Further objects and advantages will appear in the subjoined detail description.

The accompanying drawings illustrate one embodiment of the invention:

Figure 1 is a side elevation of a stoping 35 machine embodying the invention.

Fig. 2 is an enlarged vertical mid section of the upper portion of the machine shown in Fig. 1.

Fig. 3 is an inverted plan view from line 40 indicated by x^3-x^3 , Fig. 2.

Fig. 4 is a plan section on line indicated by x^4-x^4 , Fig. 2.

Fig. 5 is an inverted plan section on line indicated by x^5-x^5 , Fig. 2.

45 Fig. 6 is a plan section on line indicated by x^6-x^6 , Fig. 2.

Fig. 7 is an inverted plan view on line indicated by x^7-x^7 , Fig. 2.

50 Figs. 8, 9 and 10 are plan sections on lines indicated by x^8-x^8 , x^9-x^9 , and $x^{10}-x^{10}$, respectively.

Fig. 11 is a sectional plan view on the irregular line indicated by $x^{11}-x^{11}$, Fig. 2.

Fig. 12 is a sectional detail on line indicated by $x^{12}-x^{12}$, Fig. 2.

55 Fig. 13 is a perspective view of the valve shown in Figs. 2, 11 and 12.

In the drawings the invention is embodied in a stoping machine, but it is understood that certain features of the invention hereinafter described are applicable to drilling machines other than stoping machines. In Fig. 1 the feed cylinder of a stoping machine is indicated at 1 and the feed piston at 2 and next to the feed cylinder is an air 60 chest 3 which may be of any well known construction and which contains a reciprocative valve 4 of any well known or desired construction. Dowel pins 5 may be employed, if desired, to prevent relative rotation of the 65 cylinder 1 and air chest 3.

Next to the air chest 3 is a water chest 6 and, if desired, dowel pins 7 may be employed as shown to prevent relative rotation between the air chest and water chest.

75 Next to the water chest 6 is a cylinder 8 containing a plunger or hammer 9 adapted to work therein and the cylinder 8 also contains an anvil 10 having a reduced head 11 adapted to be struck by the hammer 9 in 80 a manner well understood in the art.

It is readily understood that it is preferable to extend the air and water tube of a machine of this description a short distance into the air and water duct of the drill 85 steel so as to minimize leakage of the air and water around the head of the drill steel when the drilling machine is in operation and such construction is not new; but when the air and water tube is thus inserted in the drill steel, it frequently occurs that

90 after the machine has been in use for some time the drill steel wears away the bore of the chuck in such manner that the drill steel is not always perfectly alined with the air and water tube but is disposed at an angle thereto. After such wearing of the chuck the head of the drill steel is sometimes so eccentric to the axis of the anvil that the discharge end of the air and water tube is pinched or broken off; and it is to 95 overcome these difficulties that some of the

principal features of the invention are provided and these features will now be described.

The anvil 10 is provided in its drill-steel 5 engaging end with a guide way in the form of a recess 12 of any suitable shape. In the drawings the recess 12 is circular but it is understood that it may be hexagonal or any other shape. At the bottom of the recess 10 12 is an annular groove 13 around a boss 14 which engages the head 15 of a drill steel 16, said head being of appropriate shape to fit the recess 12 and to be guided by the sides of the recess so as to maintain 15 the head end of the drill steel, that receives the blows from the anvil, concentric with said anvil and its boss 14.

The cylinder 8 is provided internally with an annular shoulder 17 against which rests 20 a chuck 18 which may be of the ordinary construction, the bore 19 of said chuck being of suitable shape to fit the drill steel 16 that, as is well known, may be of any suitable cross sectional form.

25 The anvil 10 is provided with an axial bore 20 into which projects one end of an air and water tube or conduit 21, the outer end of said tube projecting beyond the face of the boss 14 into the recess 12 and into 30 the bore or duct 22 of the drill steel 16. In the drawings the depth of the recess 12 is the same as the distance that the tube 21 projects beyond the face of the boss 14 in consequence of which the outer end of 35 the tube is flush with the outer face of the anvil 10.

The cylinder 8 is provided with air inlet ports 23, 24 and with air valve ports 25, 26, said ports 23 to 26 inclusive extending 40 through the water chest 6 and into the air chest 3 and communicating with the valve chamber 27 of said air chest.

The valve chamber 27 is provided with an air intake or intakes 28 and with exhaust 45 ports 29, 30. One of the exhaust ports 29 is provided with a plug 31 and is connected by a duct 32 with a valve chamber 33 having a rotary valve 34 adapted to be turned by a suitable handle 35, said valve chamber 50 33 being formed in the water chest 6. The valve chamber 33 communicates by a duct 36 with a nozzle chamber 37 which is provided with a water nozzle 38 projecting into the intake end of the air and water tube 21, 55 the portion of said nozzle within said tube being of less outside diameter than the inside diameter of the tube 21 so that air admitted through the duct 36 to the nozzle chamber 37 will discharge around the nozzle 60 38 into the tube 21 to accelerate the flow of water issuing from the nozzle 38.

The rear end of the nozzle 38 communicates with a water duct 39 which receives its supply of water through a water supply 65 pipe 40 provided with a valve 41.

The valve 34 is provided with a recess 42 forming a spring chamber containing a coil spring 43, one end of which presses against the bottom of the valve chamber 33 and the other end against the valve 70 34 so as to hold said valve tight against the inner face of a bushing 44 that is screw-threaded into the outer end of the valve chamber 33, the shaft 45 of the valve projecting through said bushing. The valve 75 recess 42 is provided with a port 46 adapted to register with the duct 32 when the valve 34 is turned into appropriate position for that purpose. The valve recess 42 is also provided with a port 47 adapted to 80 register with a duct 48 when the valve 34 is turned to the appropriate position, the ports 46, 47 being at different points circumferentially of the valve so that only one of said ports at a time may be turned into open 85 position and so that both may be closed when desired.

The duct 48 communicates with one of the air intakes 28 so that when desired live air or air under comparatively high pressure 90 may be inducted into the tube 21 to cause greater acceleration of the flow of the water in the tube than can be effected by exhaust air from the cylinder 8.

The nozzle 38 is provided with an annular 95 flange 49 which is seated in the bottom of a recess 50 of the water chest 6. Seated against the flange 49 is a washer 51 which is brazed or otherwise firmly fixed to the inner end of the tube 21 so as to form an annular flange on said tube. The flange 51 is tightly held against the flange 49 by a bushing 52 screw-threaded into the recess 50 and against the flange 51, the tube 21 extending through said bushing. 100

Air is admitted to the valve chamber 27 through the air intake 28 which extends into a throttle device 53 of any well known or desired construction, the throttle handle being indicated at 54 and said throttle controlling the flow of air from the air supply hose 58 to the machine in a manner well understood in the art. 105

Ears or lugs 55, 56 on the cylinders 1 and 8 respectively and bolts 57 hold the cylinders, throttle device 53, and air and water chests 3, 6 in assembled position. 115

In practice, assuming that the hose 58 is connected with a suitable compressed air supply, not shown, and that the water pipe 120 40 is connected with a water supply, the operator, to drill, will operate the throttle handle 54 to admit compressed air through the duct 28 into the valve chamber 27. Assuming, for example, that the parts are in the 125 position shown in Fig. 2, the air thus admitted will force the valve 4 from the position shown toward the opposite end of the valve chamber so as to admit air through the port 23 into the cylinder 8 to force the hammer 130

9 on its in or idle stroke. When the hammer moves sufficiently far to uncover the port 26, air will flow through said port into the valve chamber 27 to force the valve 4 into the position shown in Fig. 2 to admit air through the port 24 so as to force the hammer 9 on its out or working stroke, and said hammer will strike the anvil 10 so as to deliver a blow to the drill steel 16 in order to cut the material engaged by the drill steel. Owing to the head 15 resting in and being guided by the recess 12, it is clear that the duct 22 of the drill steel will always be axially alined with the tube 21 so that the end of the tube 21 projecting into the duct 22 will not be injured by the drill steel striking it, as often occurs in devices not provided with this feature of my invention.

The valve 4 and hammer 9 continue to reciprocate in the manner above described so as to deliver a succession of blows to the anvil 10.

To minimize the production of dust and to wash away the borings created by the drilling steel in the cutting operation, under normal working conditions, the operator will turn the handle 35 to bring the port 46 into registration with the duct 32 so that exhaust air will flow from the valve chamber 27 through said duct and port into the recess 42, thence through the duct 36 and nozzle chamber 37 into the tube 21 to accelerate the motion of the stream of water flowing through said tube so as to wash away the borings or cuttings from the hole being drilled. Thus, normally, only the exhaust air from the cylinder is used to accelerate the flow of the water, but in some instances, especially when the drill steel is working in clay or other substances of like nature, it may be advisable to impel the water into the hole with great force so as to force the clay or other substance out of the hole and out of the grooves of the drill steel. To do this the operator will turn the handle 35 so as to move the port 47 into registration with the duct 48 so as to admit live air through said duct and port into the valve recess 42, thence through the duct 36 to the nozzle chamber 37 and thence to the tube 21 to accelerate the flow of water in said tube and practically blow the clay or other substance out of the hole and grooves of the drill steel so as to greatly facilitate the drilling operation.

I claim:

1. A drilling machine comprising a cylinder, a hammer reciprocating in said cylinder, an anvil to receive blows from the hammer, said anvil having a recess, a drill steel having its head in the recess, a tube extending through the anvil and projecting into said recess, and a chuck in the cylinder for the drill steel.

2. A drilling machine comprising a cylin-

der, an anvil in the cylinder provided with a recess, a drill steel having its head in the recess, there being a boss at the bottom of said recess, a hammer in the cylinder to strike the anvil, a tube extending through the boss and projecting into said recess, and a chuck in the cylinder for the drill steel.

3. A drilling machine comprising a cylinder, a chuck in the cylinder, a drill steel in the chuck having a duct, an anvil in the cylinder provided with guide means for the head of the drill steel, a hammer in the cylinder to strike the anvil, and a tube extending through the anvil and projecting into the duct in the drill steel.

4. A drilling machine comprising a cylinder, a hammer in the cylinder, a water chest having a recess, a nozzle having a flange in the recess, a tube extending through the hammer and provided with a flange engaging the flange of the nozzle, said nozzle projecting into said tube, means to supply water to the nozzle, and a bushing in the recess around the tube to hold the flanges in place.

5. A drilling machine comprising a cylinder, a hammer in the cylinder, a water chest having a recess, a nozzle having a flange in the recess, a tube extending through the hammer and provided with a flange engaging the flange of the nozzle, said nozzle projecting into said tube, means to supply water to the nozzle, a bushing in the recess around the tube to hold the flanges in place, and means to supply air to the tube around said nozzle.

6. A drilling machine comprising a cylinder, a hammer in said cylinder, means to supply compressed fluid to said cylinder to reciprocate the hammer, a drill steel having a duct, a tube discharging into said duct, means to supply water to said tube, connections between the cylinder and said tube and between the compressed fluid supply and said tube, and means to change the connections at will to supply either exhaust fluid or full pressure fluid to the tube.

7. A drilling machine comprising a cylinder, a hammer in the cylinder, a water chest at one end of said cylinder having a nozzle chamber, a tube extending through the hammer and fastened to the water chest, a nozzle projecting into said tube, a duct to carry water to said nozzle, an air chest having a valve chamber, intake and exhaust ports extending from the air chest to the cylinder, a valve in said valve chamber to control the intake and exhaust ports, an air intake communicating with the valve chamber, a second valve chamber, a duct extending from the second valve chamber to the nozzle chamber, an exhaust port for the first valve chamber, a duct leading from the last named exhaust port to the second valve chamber, a duct leading from the air intake to the second valve chamber, and a valve in said

second valve chamber to control the ducts leading thereto.

8. In a drilling machine provided with a hammer, an anvil having a recess to receive the head of the drill steel, and a water tube extending through the anvil and projecting into said recess.

9. In a drilling machine provided with a hammer, an anvil having means to guide 10 the head of a drill-steel, and a water tube

extending through the anvil and projecting beyond the drill-steel engaging face of said anvil.

Signed at Los Angeles, California, this 11th day of January, 1917.
